 ors to Hytron Corporation, a corporation of
 Massachusetts

Application March 16, 1944, Serial No. 526,742

10 Claims. (Cl. 93—49)

1

This invention relates to a box end folding machine for the sleeve-type box wherein flanged box ends are inserted into a box.

Heretofore the packaging of merchandise in a sleeve-type box where the flanged ends are inserted into the box and thereafter secured has been done by a number of different operators some of whom fold both ends and insert one end into the box body, thereafter other operators pack the merchandise in the box and insert the other end. The hand operation of folding and inserting the ends of the box is comparatively slow and a comparatively large number of operators must be utilized.

One of the objects of this invention is to provide a machine which will accomplish the hand operation now used in a sleeve-type box for packaging merchandise.

Another object of the invention is to provide a machine which may be utilized by the operator who places the merchandise in the box so that while the operator has this box in his hand he may insert the end mechanically.

Another object of the invention is to provide an arrangement so that both ends of the box may be inserted at one time simultaneously after the merchandise has been placed in the box.

Another object of the invention is to provide a machine which may be power operated so that the effort in providing the mechanical motion necessary need not be physically applied.

A more specific object of the invention is to provide an arrangement so that opposite edges of the end of the box are engaged and definitely positioned in place quickly and without manual handling.

With these and other objects in view, the invention consists of certain novel features of construction, as will be more fully described and particularly pointed out in the appended claims.

In the accompanying drawings:

Figs. 1, 2, and 3 are sectional views somewhat diagrammatic, illustrating the operating parts of the machine in three successive positions of operation which these parts assume in performing their function;

Fig. 4 is a top plan view with the deck plate of the machine broken away and illustrating moving parts of the machine which are illustrated in the three previous figures;

Fig. 5 is a sectional view illustrating the actuating member as engaging an arm through which the mechanism of the machine is actuated;

Fig. 6 is a sectional view illustrating the actu-

2

ating member as having moved the arm to a different position;

Fig. 7 is an elevation of the guide for the box end flanges shown by itself;

Fig. 8 is a perspective view illustrating the main shaft, the actuating member thereon, and the two members which engage the box ends;

Fig. 9 is a perspective view of one of these box-end engaging members;

Fig. 10 is a perspective view of the box end partially inserted into the box body;

Fig. 11 is a perspective view broken away and illustrating this same box end with its engaging members in the position which they assume in having moved the end into the position shown in Fig. 10;

Fig. 12 is a perspective view with the box end moved to completely inserted position; and

Fig. 13 is a perspective view of a fragmental portion of the box with its end prior to any folding and also illustrating fragmentally the guides which engage the box-end flanges.

In proceeding with this invention, we provide a deck or table support on which a box which is to have its ends folded into the body of the box is positioned. This table or deck is suitably supported on legs and has the most of its operating mechanism, so far as bulk is concerned, positioned beneath it. The table is so arranged that an operator may be seated at the machine and the actuation may be controlled by a foot pedal. The deck or supporting plate is provided with openings through which the members which do the folding of the box ends swing upwardly to engage the box ends which are positioned over the openings to then fold both box ends simultaneously into the box body. The box ends are usually provided with flanges extending outwardly from each box end which are engaged and folded by means of a guide during the movement of the ends into the body. In order to effectively position both edges of each box end we have one member which engages the hinged edge and another member which engages the end at a location distant from the hinge for this positioning and by this arrangement effectively positions each end at right angles to the axis of the body.

With reference to the drawings 15 designates the deck plate upon which the box 16 is positioned in order that its ends 17 may be folded into the body of the box. The box body is designated generally 18 (see Fig. 13) while the ends 17, as shown in Figs. 10 to 13, are provided with flanges 19, 20, and 21, and 22, the flange 22 being hinged along the dotted line 23 (Fig. 13) to

the box body. It is desired that this end 17 be folded into the body 18 so that the flanges 19, 20, 21, and 22 may lie in the positions shown in Fig. 12.

The plate upon which this box 16 is supported is suitably positioned on a framework designated generally 23a and this plate is provided with openings 24, 24' through which suitable means swing upwardly to engage the box ends which extend over these openings so as to fold the box ends into the body of the box. Each of the ends are acted upon at the same time by similar members which operate in opposite directions so as to accomplish this result. We will describe the unit for one box end and it will be understood that the other unit is similar except caused to rotate in the opposite direction.

A shaft 25 (see Fig. 8) is supported in bearings 26 and 27 (Fig. 4) which shaft has provided at its forward end, either integrally therewith or separately attached and fixed thereto, a member designated generally 28 (see Fig. 8), which is joined to the shaft by a portion 29 positioning the member 28 so that as rotation of the shaft occurs it will swing upwardly above the supporting plate 15 to engage the box end. This member 28 is cut out as at 29a providing supporting arms 30 and 31 which support a pivot pin 32 upon which the projecting portion 33 (see Fig. 9) of a second box-end engaging member, designated generally 34 and shown in perspective at Fig. 9, is hingedly mounted. This member is generally L-shaped with a block portion 35 slotted as at 36 and provided with an opening 37.

An auxiliary shaft 38 (see Fig. 8) also has a bearing in this member 28 and the connecting portion 29 and is provided at one end with a fixed arm 39 while intermediate its ends it is provided with an arm 40 fixed to this shaft 38 and located in a slot 41 in the member 28. This arm 40 is slotted as at 42 and a link 43 connects this arm 42 to the member 34 by pins 44 at one end extending through the arm 40 and a pin 45 at the other end extending through the opening 36 in the block 35 of member 34. A spring 46 attached as at 47 (Fig. 2) to the member 34 and by means of the hook 48 (see also Fig. 8) to the member 28 serves to swing the member 34 about its pivot 32 until its block portion 35 engages the member 28 as shown in Fig. 8.

An actuating member designated generally 50 (see Figs. 8 and 11) and comprising a pulley 51, rotatably mounted on the shaft 25 and having an abutment 52 with an added friction wheel 53 mounted therein for engagement with the arm 39, is carried by this pulley 51. A flexible member, such as chain 54, is wrapped about the drum portion 55 (see Fig. 4) and is held thereon by a suitable flange 56 so that as this chain is pulled upon, the pulley will rotate on the shaft and engage the arm 39. The shaft 25 is equipped with sleeve 56a (Fig. 4) which is held securely thereon by means of set screws 57 so as to fix the sleeve on the shaft. A suitable flexible member 58 is attached thereto as at 59 and wrapped about the sleeve while a spring 60 is attached to this flexible member and also to the framework of the machine so as to rotate the shaft tending to withdraw the member 28 from the box to a position beneath the supporting deck plate. This spring is of a character which will apply less tension than the spring 46 which tends to swing the member 34 about its pivot 32. The rotation due to the action of this spring is limited by the abutment 52 engaging the shoulder 62 of a bar

63 which is bolted to the top of the deck plate as at 64. The bar also has an overhanging arm 65 providing a finger 66 carrying a stop 67 for the limit of rotation of the shaft 25 and its carrying members in the opposite direction as will be further pointed out. This stop 67 may be adjusted by loosening set screw 68 which holds it in adjusted position.

At a location over each of the openings through 10 which the members 28 and 34 extend a guard 70 (Figs. 1, 2, 3) is provided which extends upwardly from the deck 15 to a location substantially over the end of the box 16. This is of generally arcuate shape. This guard 70 supports the guide 71 which is shown in face view in Fig. 7 and consists of the horizontal portion 72 and two vertical portions 73 and 74, all of which are beveled as at 75 (see Figs. 2, 3, and 13) while this member 71 is secured in place to the guard by suitable bolts at 76 (shown in Figs. 2 and 3).

The description thus far has been directed to the mechanism for folding inwardly the left-hand box end as illustrated in views 1 to 4. A duplicate mechanism for operating on the right-hand end of the box is also illustrated and which 15 is a duplicate in all respects as heretofore described. Similar reference characters except for the addition of the prime will therefore be used to characterize any of the duplicate right-hand mechanism. The actuating members 50 and 50' (Figs. 2 and 3) are actuated by means of the flexible members 54 and 54' which are operated simultaneously by reason of being connected to a yoke 80 as by means of the ears 81 and 81'. This yoke is moved downwardly so as to rotate 20 the actuating members 50 and 50' by the movement of post 82 which is connected to the yoke 80 through leaf springs 83.

This post 80 may be moved downwardly by any 25 suitable means, such for instance as by a foot pedal but is more desirably actuated by means of a solenoid designated 84 into which the post 82 extends as a core and which will be drawn downwardly into the solenoid when the same is energized. Energy may be supplied to this solenoid by the line 85 and 86 (see Fig. 3), the latter of 30 which has a mercury switch 87 in the line so that when the post 82 nears the bottom of its stroke the yoke 80 will swing the switch 87 downwardly by means of its being mounted on the tiltable platform 88, hinged as at 89 and returned to horizontal by spring 90, so as to break the circuit and permit the post to again raise to starting position 35 through the action of the springs 60 and 60' which will pull the yoke upwardly. A suitable switch 91 may be located convenient to the operator so that it may be closed until the post 82 has reached the bottom of its stroke when the line will be automatically opened at the mercury switch 87 and the operator will release the closing 40 of the line by switch 91 until ready for a subsequent operation.

In operation, when the switch 91 is closed and the post 82 moves downwardly, the pulleys 50, 50' will be oppositely rotated to bring, in the case of pulley 50, the block 52, and its anti-friction member 53 thereon into engagement with the arm 39 of the auxiliary shaft 38. The spring 46 will be sufficiently strong so that rotation of the shaft 25 will occur before the auxiliary shaft 38 will turn in its bearings. Accordingly, the shaft 25 will turn bringing the member 28 from the position shown in Fig. 1 to the position shown in Fig. 2 whereby the flange 22 of the box end 17 will be engaged and the box end forced into the

body 18 of the box 16 as shown in Fig. 2. At this point the member 28 will have reached the limit of its stroke having forced the flange 22 so that it lies against the deck 15 and therefore the shaft 25 can turn no further. Force, however, being applied to the arm 39, will then start to rotate the shaft 38 in its bearings and start to swing the second member 34 from its position as shown in Fig. 2 to its position as shown in Fig. 3, thereby engaging the edge of the box which is away from the hinge connection and forcing it into the sleeve-like box so that this end 17 will be at right angles to the wall of the box as shown in Fig. 3. As the member 34 reaches this position, the arm 39 will engage the stop 61 (dotted lines Fig. 5) mounted in the projecting portion 66 so as to limit any further movement of this auxiliary shaft in its bearings. At this point the mercury switch will be tipped to break the circuit and the solenoid being de-energized will permit the post 82 to ascend or move upwardly and the parts returned to starting position after which the box may be removed and a fresh box with unclosed ends positioned for a subsequent similar operation.

It will be apparent that as the box end illustrated in Fig. 13 moves upwardly due to engagement by the member 28 its flanges, 19, 20, 21 will be engaged by the several guiding faces 15 and swung from their position in the plane of the member 17 to a position at right angles to this end 17 as shown in Figs. 10, 11, and 12.

A hole 49 in the box end engaging member 34 registers with hole 49' in the box so that the pins of a tube which project through these holes may be received therein without damaging them.

We claim:

1. In a box end folding machine, a support for the box, box end engaging means comprising a pair of movable members, means for initially moving said members together for movement of the box end and subsequently stopping one of said members while the other member continues to move the box end into final position.

2. In a box end folding machine, a support for the box, a member mounted to swing about an axis for engagement with the box end adjacent its hinge connection to the body of the box, for moving the box end into the body, a second member rotatably mounted in relation to the first member also engageable with the box end adjacent its edge distant from its hinge connection to the body of the box for moving such edge into the body, means to initially move both members together and subsequently the second member alone in moving the box end into the box body.

3. In a box end folding machine, a support for the box, a member mounted to swing about an axis for engagement with the box end adjacent its hinge connection to the body of the box for moving the box end into the body, a second member rotatably mounted in relation to the first member and eccentrically to its axis of rotation also engageable with the box and adjacent its edge distant from its hinge connection to the body of the box for moving such edge into the body, means to initially move both members together and subsequently the second member alone in moving the box end into the box body.

4. In a box end folding machine, a support for the box, a pair of box end engaging means one for each end of the box and each comprising a pair of movable members, means for initially moving said members together for engagement of the box ends and subsequently stopping one

of said members while the other member continues to move the box end into final position.

5. A machine for folding a box end comprising a supporting deck for the box provided with an opening therethrough, a main shaft rotatably mounted in bearings and provided with an eccentrically mounted member movable through one of said openings upon rotation of the shaft to engage the hinged edge of a box and move it into the box body, a spring for returning said shaft and member, a second member rotatably supported by the first member on an axis eccentric to the axis of said shaft and movable with reference to the first member to engage the edge of the box end distant from its hinge connection and move it into the box body, an auxiliary shaft carried by the first member located eccentric to the axis of the main shaft and provided with a pair of arms fixed thereto, a link between one of the arms and the second member for moving it about its axis of rotation upon rotation of the auxiliary shaft, a second spring of greater tension than the main shaft spring for returning said second member, an actuating member rotatable about the axis of the main shaft to engage said other arm and initially move said auxiliary shaft and both members thereon through said opening until the first member is limited in its movement by the deck and to then move the second member with reference to the first member against the action of the second spring to further move the box end into the box body and means to move the actuating members.

6. A machine for folding box ends comprising a supporting deck for the box provided with openings therethrough, a pair of main shafts rotatably mounted in bearings each provided with an eccentrically mounted member movable through one of said openings upon rotation of the shaft to engage the hinged edge of a box end and move it into the box body, a spring for returning each shaft and member and a second member rotatably supported by each first member on an axis eccentric to the axis of said shaft and movable with reference to the first member to engage the edge of the box and distant from its hinge connection and move it into the box body, an auxiliary shaft carried by each first member located eccentric to the axis of the main shaft and provided with a pair of arms fixed thereto, a link between one of the arms and the second member for moving it about its axis of rotation upon rotation of the auxiliary shaft, a second spring of greater tension than the main shaft spring for returning each said second member, a pair of actuating members each rotatable about the axis of each main shaft to engage said other arm and initially move the auxiliary shafts and both members thereon through said openings until the first members are limited in their movement by the deck and to then move the second members with reference to the first members against the action of the second springs to further move the box ends into the box body and common means to move both of the actuating members.

7. A machine for folding box ends comprising a supporting deck for the box provided with openings therethrough, a pair of main shafts rotatably mounted in bearings each provided with an eccentrically mounted member movable through one of said openings upon rotation of the shaft to engage the hinged edge of a box end and move it into the box body, a spring for returning each shaft and member and second

member rotatably supported by each first member on an axis eccentric to the axis of said shaft and movable with reference to the first member to engage the edge of the box end distant from its hinge connection and move it into the box body, an auxiliary shaft carried by each first member located eccentric to the axis of the main shaft and provided with a pair of arms fixed thereto, a link between one of the arms and the second member for moving it about its axis of rotation upon rotation of the auxiliary shaft, a second spring of greater tension than the main shaft spring for returning each said second member, a pair of actuating members each rotatable about the axis of each main shaft to engage said other arm and initially move the auxiliary shafts and both members thereon through said openings until the first member is limited in its movement by the deck and to then move the second member with reference to the first member against the action of the second spring to further move the box ends into the box body and common means to move both of the actuating members in opposite directions to move the box end engaging members toward each other.

8. A machine for folding a box end comprising a supporting deck for the box provided with an opening therethrough, a main shaft rotatably mounted in bearings and provided with an eccentrically mounted member movable through said opening upon rotation of the shaft to engage the hinged edge of a box end and move it into the box body, a spring for returning said shaft and member, a second member rotatably supported by the first member on an axis eccentric to the axis of said shaft and movable with reference to the first member to engage the edge of the box end distant from its hinge connection and move it into the box body, an auxiliary shaft carried by the first member located eccentric to the axis of the main shaft and provided with a pair of arms fixed thereto, a link between one of the arms and the second member for moving it about its axis of rotation upon rotation of the auxiliary shaft, a second spring of greater tension than the main shaft spring for returning said second member, an actuating member rotatable about the axis of the main shaft to engage said other arm and initially move said auxiliary shaft and both members thereon through said opening until the first member is limited in its movement by the deck and to then move the second member with reference to the first member against the action of the second spring to further move the box end into the box body, means to move the actuating member, and a guide standing upwardly from said deck through which said member moves said guide serving to fold flanges on the box end as the end is moved into the box body.

9. A machine for folding a box end comprising a supporting deck for the box provided with an opening therethrough, a main shaft rotatably mounted in bearings and provided with an eccentrically mounted member movable through said opening upon rotation of the shaft to engage the hinged edge of a box end and move it

10. into the box body, a spring for returning said shaft and member, a second member rotatably supported by the first member on an axis eccentric to the axis of said shaft and movable with reference to the first member to engage the edge of the box end distant from its hinge connection and move it into the box body, an auxiliary shaft carried by the first member located eccentric to the axis of the main shaft and provided with a pair of arms fixed thereto, a link between one of the arms and the second member for moving its axis of rotation upon rotation of the auxiliary shaft, a second spring of greater tension than the main shaft spring for returning said second members, an actuating member rotatable about the axis of the main shaft to engage said other arm and initially move said auxiliary shaft and both members thereon through said opening until the first member is limited in its movement by the deck and to then move the second member with reference to the first member against the action of the second spring to further move the box end into the box body, means to move the actuating member, a guide standing upwardly from said deck through which said members move said guide serving to fold flanges on the box end as the end is moved into the box body and a guard over said guide and deck opening.

10. A machine for folding box ends comprising a supporting deck for the box provided with openings therethrough, a pair of main shafts rotatably mounted in bearings each provided with an eccentrically mounted member movable through one of said openings upon rotation of the shaft to engage the hinged edge of a box end and move it into the box body, a spring for returning each shaft and member and a second member rotatably supported by each first member on an axis eccentric to the axis of said shaft and movable with reference to the first member to engage the edge of the box end distant from its hinge connection and move it into the box body, an auxiliary shaft carried by each first member located eccentric to the axis of the main shaft and provided with a pair of arms fixed thereto, a link between one of the arms and the second member for moving it about its axis of rotation upon rotation of the auxiliary shaft, a second spring of greater tension than the main shaft spring for returning each said second member, a pair of actuating members each rotatable about the axis of each main shaft to engage said other arm and initially move the auxiliary shafts and both members thereon through said openings until the first members are limited in their movement by the deck and to then move the second members with reference to the first members against the action of the second springs to further move the box ends into the box body, means to move the actuating members, and a pair of guides standing upwardly from said deck through which each set of said members move said guide serving to fold flanges on the box end as the ends are moved into the box body.

ALBERT H. RINES.
